(57) **CLAIM**

The ornamental design for an card holder, as shown and described.

DESCRIPTION

FIG. 1 is a front perspective view of the card holder;
FIG. 2 is a front perspective view of the card holder with an unclaimed card appearing in broken lines;
FIG. 3 is a rear perspective view of the card holder;
FIG. 4 is a front elevation view of the card holder;
FIG. 5 is a rear elevation view of the card holder;
FIG. 6 is a top plan view of the card holder;
FIG. 7 is a bottom plan view of the card holder;
FIG. 8 is a side elevation view of the card holder; and,
FIG. 9 is an opposite side elevation view of the card holder. Broken lines appearing in the drawings are intended to be for illustrative purposes only and form no part of the claimed design.
